CONSTANT SUPPORT DEVICE

Leonard S. Suozzo, Hackensack, N.J., assignor to Bergen Pipe Support Corp., New York, N.Y., a corporation of New York

Application August 3, 1956, Serial No. 601,975

5 Claims. (Cl. 248—54)

2

Fig. 3 is a view in side elevation of the upper forward portion of support means and illustrating elements of a combined travel stop and indicator means;

5 Fig. 4 is a top plan view of the apparatus shown in Fig. 1, certain parts being broken away and other parts being in cross section for better illustration;

Fig. 5 is a view taken along line 5—5 of Fig. 4;

Fig. 6 is an elevation view as seen from the left of Fig. 4; and

10 Fig. 7 is a view in side elevation of a modified form of the invention, parts being omitted for better illustration of other parts.

Referring now to the drawings, wherein like reference numerals denote corresponding parts throughout the several views, and more particularly to Figs. 1 through 6, a support that is generally indicated by numeral 10 comprises a horizontally disposed cylindrical protective housing 11, having an elongated slot 12, and a stationary backing unit 13 welded or otherwise secured to the forward

20 end of the housing. Backing unit 13 includes a plate 14 that extends across the forward end of the housing and that has a central through aperture 15. Integral with plate 14 is a forwardly projecting top flange 16 having a pair of drill holes 17 for reception of suitable connectors,

25 such as bolts (not shown) for affixing the support to an overhead structure such as a beam. A pair of spaced parallel plates 20 are welded to plate 14 and flange 16 and are provided with aligned arcuate slots 21. An indicator plate 22, that is best shown in Fig. 3 is positioned adjacent each slot 21 and is graduated as indicated at 23 for purposes that will be explained further along herein;

30 A lever 25 includes a pair of parallel arms 26 that are maintained in the illustrated spaced apart relation by a hub 27. A shaft 28 extends through hub 27 and is supported at its ends by plates 26. A pin 30 is carried by plates 26 and registers at its ends with corresponding arcuate slots 21. Pin 30 is parallel to shaft 28. Each end of the pin is provided with an indicator marking 31 that coacts with the graduations 23 to indicate the angular position of lever

35 25 and the extent of travel of a load that is supported by the apparatus. Pin 30 also serves as a stop to limit pivotal movement of the lever to the extent allowed by slots 21. Each of a pair of pivot pins 32 is carried by a corresponding lever arm 26. These pins are coaxial and are connected to elements that will be described further along

40 45 herein.

45 Secured to and extending rearwardly of plate 14 is a cage 33 that serves as a guide means for parts to be described. The guide means consists of a pair of spaced parallel plates 34 that are disposed to opposite sides of aperture 15 and a bottom plate 35 that is disposed below aperture 15. Plates 34 and 35 are welded to each other and to plate 14 to obtain a sturdy, rigid, unitary structure. Plates 34 are formed with aligned slots 36 that define a horizontal path.

50 55 Reference is now had to Figs. 1, 4 and 5 for an understanding of the construction of a spring mechanism which preferably comprises a single helical compression spring 40 that is positioned wholly within housing 11 and that bears at one end against plate 14 of stationary backing unit 13 and at its other end against a movable backing unit 41. The parts are so constructed and arranged that the longitudinal axis of the spring is at all times stationary and parallel to or coincident with the path defined by slots 36.

60 65 Backing unit 41 comprises a circular end plate 42, having a central through opening 43, a cylindrical side wall 44 and an annular flange 45 against which the rear end of spring 40 bears. Cylindrical side wall 44 maintains the spring in proper alignment. The movable backing unit also includes an arm 46 that is threaded at

This invention relates to a support for various types of loads, including pipes or the like. The invention pertains, in one of its more specific aspects, to a spring-loaded constant support device that is adapted to permit vertical movement of a load and simultaneously subject the load to a substantially constant supporting force.

This application is a continuation-in-part of my copending patent application Serial No. 555,010, filed December 23, 1955, now Patent 2,903,213, and entitled "Constant Support Device."

The purposes and functions of devices constructed in accordance with this invention and the objects of this invention are essentially the same as those disclosed in my said copending application, to which reference may be had for details.

The present invention has for an additional object the provision of a constant support device that not only embodies the principal features of certain of the devices disclosed in my said copending application, but further is simpler and even more compact in design, less expensive in manufacturing cost and more efficient in operation.

As in the case of devices according to my said copending application, the device of this invention includes a support and a spring mechanism comprising at least one spring that defines an axial through opening which is stationary relative to the support. One of the features of this invention resides in the provision of rod means within the spring opening and forming separate pivotal connections with a movable backing unit of the spring mechanism and with a lever that is also pivotal with respect to the frame and a load-carrying unit. There is provided an adjustable means for varying the effective length of the rod means in a manner to correspondingly vary the loading on the spring and the distance between the pivotal connections of the rod means with the movable backing unit and the lever. The parts are so constructed and arranged that variations in the effective length of the rod means and resulting variations in the spring loading do not materially effect the moment produced by the spring force and the rod means and associated elements in use. In other words, the parts are interrelated and cooperate in a manner whereby the device exerts a substantially constant supporting force throughout its range of adjustability.

The objects, together with the advantages and benefits obtainable by the use of the apparatus of this invention, will be readily understood by persons skilled in the art upon reference to the following detailed description taken in conjunction with the annexed drawings, which respectively describe and illustrate several forms of apparatus embodying the invention.

In the drawings:

Fig. 1 is a view in central longitudinal vertical cross section of a spring support device constructed in accordance with the invention;

Fig. 2 is a view in enlargement taken along line 2—2 of Fig. 1;

one end and that extends through plate opening 43. A nut 47 engages the threaded end of arm 46 and forms a permanent connection therewith preferably by welding, as indicated at 48. A washer 49 is interposed between plate 42 and nut 47.

Integral with arm 46 is a clevis 50 which includes a pair of spaced parallel arms 51 that carry a shaft 52. A bearing sleeve 53, best shown in Fig. 5, is positioned on shaft 52, between clevis arms 51, and is formed with an annular recess 54. Coaxial with shaft 52 and disposed at each end of sleeve 53 is a combined spacer and roller 55 that registers with a corresponding slot 36 and that is adapted to move along the path defined by the guide means. Retaining rings or washers 56 are secured to the ends of shaft 52 by welding, as indicated at 57, or in any other manner known to the art.

The apparatus of this invention includes a rod means that is connected to backing unit 41 and movable with respect thereto about the axis of shaft 52 and that is connected to lever 25 and movable with respect thereto about the common axis of pins 32. The rod means comprises an eye bolt 60 having a circular head 61 that engages bearing sleeve 53 and registers with annular recess 54 thereof. It will be appreciated from an examination of Figs. 1 and 5 that eyebolt 60 is pivotal about the axis of shaft 52. The eyebolt extends through a central opening 62 in web 63 of a second clevis 64 (Fig. 2) which is movable through aperture 15 (Fig. 1). This clevis has a pair of spaced parallel arms 65 that are connected to pins 32 and are pivotal about the common axis thereof.

The effective length of the rod means and, therefore, the distance between the axis of shaft 52 and the common axis of pins 32 may be readily adjusted through the medium of a nut 66 that threadedly engages bolt 60. Nut 66 consists of a head 67, which is adapted to be turned by a wrench or other suitable tool, and an elongated tubular extension 68 (Fig. 2). A spacing sleeve 69 is carried by the eyebolt and is positioned between nut 66 and clevis web 63.

Assuming that spring 60 is under a predetermined compressive loading and that the apparatus is not carrying an external load, then the parts will be in the relative position shown in Fig. 1 with lever 25 at its extreme clockwise pivotal position about the axis of shaft 28, as allowed by pins 30 and slots 21. The spring loading may be readily increased or decreased as desired by merely turning nut 66 in the corresponding direction about the eyebolt. This will correspondingly vary the effective length of the rod means and the distance between the axes of shaft 52 and pins 32. Thus when the spring loading is increased, the effective length of the rod means is correspondingly decreased; and, when the spring loading is decreased, the effective length of the rod means is correspondingly increased.

The apparatus also includes a means that coacts with nut 66 to indicate the extent, if any, of increases or decreases in spring loading with reference to the normal spring loading for which a particular size apparatus is designed. In this connection I provide a tubular member 70 having an end wall 71 which is apertured to receive reduced diameter end 72 of the eyebolt. The tubular member is affixed to the eyebolt preferably by a weld 73. Member 70 has a pair of diametrically opposed slots 74 that serve as viewing windows. Adjacent each slot is a scale 75 that is graduated to denote the normal spring loading and the percentage increase or decrease of such loading. As is illustrated in Fig. 2, nut extension 68 projects into tubular member 70 and is telescopically arranged with respect thereto. The free extremity of extension 68 coacts with scale 75 to indicate variations in the spring loading as will be evident from an examination of Figs. 1 and 2.

Reference is next had to Figs. 1 and 4 for an understanding of the construction of a load-carrying unit 76

that is secured to lever arms 26. Unit 76 comprises an oblong ring 77 which is provided with a pair of coaxial pins 80 that are journaled in the lever arms and maintained thereon by retaining rings or the like 81. The axis of pins 80 is parallel to the axes of shaft 28, pins 32 and shaft 52. A block 82 is positioned in ring 77 and is affixed thereto by welding or otherwise. A rod 83 is threaded at its upper end for engagement with a central through tap in block 82. This rod is adapted to be connected to an arrangement of piping or other load (not shown). It will be observed that unit 76 is pivotal about the axis of pins 80.

For the purpose of briefly outlining the operation of the apparatus shown in Figs. 1 through 6, it is assumed that the parts have been assembled and are in the relative position shown in those views. With the parts so arranged, the apparatus is set up to support the normal load for which it is designed, as the free extremity of tubular extension 68 is at "0" of scale 75 (Fig. 1). The apparatus is suspended from a beam or other overhead structure by means bolts that extend through drill holes 17. The load may consist of a series of pipes that transmit a high temperature fluid. The parts are so constructed and arranged that the apparatus furnishes a substantially constant lifting support for the pipes, while permitting the pipes to move upwardly or downwardly as a result of expansion or contraction due to variations in temperature of the pipes. Downward movement of the load imparts corresponding counter clockwise movement to lever 25 about the axis of shaft 28. The lever coacts with the rod means to correspondingly move movable backing unit 41 toward the left as viewed in Fig. 1.

The balancing effect obtained by the apparatus will be recognized by persons skilled in the art upon consideration of the drawings. Reference may also be had to my said copending application which discloses several related forms of apparatus and further details of similar operation.

In the present application the axis of shaft 28 constitutes a first pivotal axis, the axis of shaft 52 constitutes a second pivotal axis, the common axis of pins 32 constitutes a third pivotal axis and the common axis of pins 80 constitutes a fourth pivotal axis. These axes cooperate with the illustrated and described parts to afford a constant support device which is capable of attaining the objectives and benefits of this invention.

Fig. 7 illustrates a modified form of the invention that is the same in a number of respects to the construction shown in Figs. 1 to 6. In the modification, a support 85 corresponds to support 10 of Fig. 1. Support 85 comprises a cylindrical housing 86 having an end plate 87 corresponding to plate 14. Housing 86 is positioned vertically instead of horizontally as in the case of housing 11. Welded to housing 86 is a bracket 88 that carries a bolt 89 for attachment to an overhead support. The spring mechanism is the same as the earlier described spring mechanism, but is positioned vertically within the housing instead of horizontally. Lever 90 is similar to lever 25 but is of somewhat different configuration. The pivotal axes of the parts are all parallel to each other but are disposed in the relative positions shown in Fig. 7. It will be observed that the fourth pivotal axis (pins 80) is beneath bolt 89, and to the side of a line extending from the second pivotal axis (shaft 52) to the third pivotal axis (pins 32) that is remote from the first pivotal axis (shaft 28).

The form of the invention shown in Fig. 7 operates in substantially the same manner as that illustrated in Figs. 1 through 6.

From the foregoing, it is believed that the objects, construction, operation and advantages of my present invention will be readily comprehended by persons skilled in the art, without further description. Although the invention has been herein shown and described in several simple and practicable forms, it is recognized that cer-

tain parts or elements thereof are representative of other parts or elements which may be used in substantially the same manner to accomplish substantially the same results. Therefore, it is to be understood that the invention is not to be limited to the exact details described herein, but is to be accorded the full scope and protection of the following claims.

I claim:

1. In apparatus of the character described, a support including a stationary first backing unit, a lever connected to the support and movable with respect thereto about a first pivotal axis, a spring mechanism carried by the support and including a second backing unit that is spaced from and movable with respect to the first backing unit, spring means disposed between and bearing against the backing units, said spring means defining a longitudinal opening, means within said opening and comprising rod means connected to the second backing unit and movable with respect thereto about a second pivotal axis, said rod means being connected to the lever and movable with respect thereto about a third pivotal axis, stationary guide means carried by the support and having at least one slot which defines a path that is substantially parallel to the axis of said opening, and coupling means connecting the rod means to the guide means and pivotally connecting the rod means to the second backing unit, said coupling means projecting to at least one side of the rod means, said coupling means registering with said slot and being movable along said path, said coupling means permitting sliding movement of the rod means and the second backing unit relative to the guide means along said path, and a load-carrying unit connected to the lever.

2. In apparatus of the character described, a support including a stationary backing unit, a lever connected to the support and movable with respect thereto about a first pivotal axis, a spring mechanism carried by the support and including a movable backing unit that is spaced from the stationary backing unit, spring means disposed between and bearing against the backing units, said spring means comprising a spring that defines a rectilinear through opening, stationary guide means carried by the support and projecting into said opening, said guide means having at least one slot which defines a path that is substantially parallel to the longitudinal axis of the spring, rod means within the opening, a shaft connected to the movable backing unit, coupling means pivotally connecting the shaft to the rod means, said coupling means projecting to at least one side of the rod means, said coupling means registering with said slot and being movable along said path, said rod means being connected to the lever and movable with respect thereto about a third pivotal axis, and a load-carrying unit connected to the lever.

3. In apparatus of the character described, a support, first and second backing units carried by the support, said first backing unit being stationary and defining a through aperture, said second backing unit being movable with respect to the first backing unit, a lever disposed to the side of the first backing unit remote from the second backing unit and movable with respect to the first backing unit about a first pivotal axis, at least one spring disposed between and bearing against the backing units, 10 said spring being compressible and defining an axial through opening, rod means within the opening and extending through the aperture, said rod means being connected to the second backing unit and the lever and being movable with respect to the second backing unit about 15 a second pivotal axis and movable with respect to the lever about a third pivotal axis, adjustable means for varying the effective length of the rod means to thereby correspondingly vary the loading on the spring and the distance between the second and third pivotal axes, indicating means carried by the rod means for denoting variations in the effective length of the rod means, stationary guide means carried by the support and projecting into said opening, said guide means having at least 20 one slot which defines a path that is substantially parallel to the axis of the spring, coupling means connecting the rod means to the guide means and pivotally connecting the rod means to the second backing unit, said coupling means projecting to at least one side of the rod means, said coupling means registering with said slot and being 25 movable along said path, and a load-carrying unit connected to the lever and movable with respect thereto about a fourth pivotal axis, said pivotal axes being spaced apart and substantially parallel.

4. Apparatus according to claim 3 wherein the axis 35 of the spring is substantially horizontal, wherein the first first pivotal axis is below the second and third pivotal axes, and wherein the third pivotal axis is between the second and fourth pivotal axes.

5. Apparatus according to claim 3 wherein the axis 40 of the spring is substantially vertical and wherein the first and fourth pivotal axes are spaced from and disposed to opposite sides of a line that is normal to the second and third pivotal axes.
